COMPENSATING DOUBLE PRESSER FOOT

Max T. Voigt, Reading, Pa.

Application July 29, 1939, Serial No. 287,316

3 Claims. (Cl. 112—235)

An object of my invention is to provide a compensating presser foot for sewing machines. Such a presser foot compensates or permits the use of a sewing machine to form a line of stitches in a portion of cloth of varying thickness as at a seam or edge.

A particular feature of my invention is to provide a compensating presser foot which may be used on either right-hand or left-hand edges of a cloth, obviating the necessity of reversing the cloth for running a line of stitches.

More specifically, my invention consists of a sewing machine presser foot having a shank adapted to fit with any one of the types of sewing machines now on the market, a yoke carried by said shank, a pivot carried by said yoke, a pair of presser shoes carried by said pivot for reciprocating and pivotal movement in a vertical plane, and a pair of springs interposed between said yoke and each of said presser shoes and stressing said presser shoes to the limit of their movement away from said yoke and on opposite sides of said pivot.

The above are a few of the features of the invention and others will appear as the nature of the invention is better understood with reference to the specification and the annexed drawing, wherein:

Fig. 1 is a side elevation of my device.

Fig. 2 is a vertical cross-section on line 2—2 of Fig. 1.

Fig. 3 is a horizontal cross-section on lines 3—3 of Fig. 1.

Fig. 4 is a bottom plan view with the shank omitted.

Fig. 5 is a fragmentary side elevation with parts broken away in vertical cross-section showing the device in operation on a seam.

Fig. 6 is a bottom plan view with the shank omitted of a modification.

Fig. 7 is a vertical cross-section of the presser shoes alone similar to Fig. 2 showing the modification of Fig. 6.

A sewing machine presser foot in accordance with my invention comprises a shank 1 made to interfit with the supporting parts of any one of the numerous types of sewing machines now on the market. At the lower end, shank 1 carries a yoke 2 of inverted U-shape in vertical cross-section having the side walls 3, which are pierced by holes through which passes a pivot 4 which may be riveted or otherwise secured to the yoke.

Mounted on pivot 4 are the presser shoes, which are substantial duplicates and of which but one will be described and which consist of 55

a body 5 having a vertical slot 6 therein closed at its upper end 7 so as to support the presser shoe on the pivot 4. The presser shoe is provided with a flat sole 8 and with an upturned toe 9, which is rounded in its horizontal aspect as seen in Fig. 4. At its inner edge, the presser shoe may be provided with a shouldered notch 10, which serves as a guide on the edge of the cloth being sewed and determines the distance of the line of stitching from the edge of the cloth. In its upper surface, the presser shoe is recessed to receive two springs 11 shown as coil springs although they may be of any convenient type which serve to stress the presser shoe to the limit of its movement away from yoke 2, and which also serve to oppose the pivoting movement of the presser shoe about the pivot 4.

The operation of my device will be evident from the foregoing. When it is desired to sew a line of stitching into a fabric having two portions of varying thickness, such as a seam or edge, one of the presser shoes rises on the pivot, as seen in the rear presser shoe in Fig. 5, and thus rides up over the thickened fabric. The springs 11 then serve to flatten out the presser shoe about its pivot while, at the same time, it remains in elevated position above the other presser shoe. Since both presser shoes are capable of this vertical reciprocating and limited pivotal movement, rows of stitches can be run adjacent either a right-hand or a left-hand edge of the fabric. It is thus unnecessary for the operator to turn the cloth or fabric being worked on around in order to sew the opposite edges. This is particularly useful in the manufacture of garments and garment parts such as collars and cuffs.

In Figs. 6 and 7 is shown a modification of my device in which the notch 10 is omitted. In this modification the presser shoes are designated 8'.

I do not intend to be limited save as the scope of the prior art and of the attached claims may require.

45 I claim:

1. A compensated double presser foot for sewing machines comprising, a shank adapted to interfit with the carrying parts of a sewing machine, a yoke carried by the end of said shank, a pivot carried by said yoke, a pair of separate presser shoes mounted on said pivot for reciprocating and pivoting movement in a vertical plane relative to each other and to said pivot, and springs interposed between said yoke and each of said presser shoes and yieldingly stressing

said presser shoes to the limit of their movement away from said yoke.

2. In a compensating presser foot for sewing machines and the like and having a shank forming a support therefor, a pair of separate presser shoes mounted for independent reciprocating and pivotal movement in a vertical plane relative to each other and to said shank, a pivot on which said presser shoes are carried, and a pair of springs interposed between said shank and each of said presser shoes on opposite sides of said pivot and stressing said presser shoes to the limit of their movement away from said shank and yieldably opposing pivotal movement thereof.

3. A sewing machine presser foot comprising, a supporting member, a pair of presser shoes

spaced vertically from said supporting member and each having a slot passing therethrough in a horizontal direction, said slots being elongated and having closed ends in a vertical direction, a 5 pivot carried by said supporting member and passing through said slots and having a diameter substantially equal to the smaller dimension of said slots so that said presser shoes are mounted for independent reciprocating and pivotal movement relative to each other and to said supporting member, and at least one spring interposed between said supporting member and each of said presser shoes and stressing said presser shoes to the limit of their movement away from said supporting member.

MAX T. VOIGT.
